(57) **CLAIM**

The ornamental design of a wheel cover and wheel, as shown and described.

DESCRIPTION

FIG. 1 is a front elevation view of a wheel cover and wheel showing our new design;

FIG. 2 is a side elevation view thereof, the opposing side view being the same; and,

FIG. 3 is a top plan view thereof, the opposing bottom view being the same.

The broken lines depict portions of the wheel cover and wheel that form no part of the claimed design.
